HARRY THOMSON, OF HOUSTON, TEXAS, ASSIGNOR TO HOWARD SMITH CO., OF HOUSTON, TEXAS, A CORPORATION.

PACKER.

Application filed August 5, 1924. Serial No. 730,146.

This invention relates to new and useful improvements in a packer.

One object of the invention is to provide a well packer adapted to form a water tight seal or joint between two pipes in a well bore.

Another object of the invention is to provide a well packer which may be set to form a water tight joint between an inner pipe and an outer pipe or the surrounding walls of the well bore, and which includes means for holding the packing in set, or expanded position.

A further object is to provide a special type of tool for setting the packer, said tool being releasable so that it may be withdrawn when the packer is set.

With the above and other objects in view, the invention has particular relation to certain novel features of construction, operation and arrangement of parts, an example of which is given in this specification and illustrated in the accompanying drawings, wherein:—

Figure 1 shows a side elevation of the packer as lowered in the well casing and in position to be set or expanded, shown partly in section.

Figure 2 shows an enlarged fragmentary vertical sectional view, showing the setting tool in active position and the packer set or expanded.

Figure 3 shows an enlarged fragmentary vertical sectional view of the packer in position to be set.

Figure 4 shows an enlarged fragmentary vertical sectional view, showing the setting tool in inactive position; and,

Figure 5 shows a cross sectional view on the line 5—5 of Figure 3.

Referring now more particularly to the drawings, wherein like numerals of reference designate similar parts in each of the figures, the numeral 1 designates the well casing, or other pipe in the well bore. The numeral 2 designates the liner to which the well screen which is to be set in the bore, is attached. In the present illustration of Figure 2 the packer is shown expanded and forming a water tight joint between this liner and the outer casing 1. Connected to the upper end of the liner 2 there is a tubular nipple 3 whose lower end is reduced, or swaged, as shown and the upper end of

this nipple is threaded into a collar 4, which, in turn, is threaded onto an annular outwardly threaded rib 5, of the ring like dog 6. The lower end of this dog 6 is vertically slotted forming flexible fingers 7, whose inner faces have ratchet teeth having a left hand pitch. The dog 6 is slidably mounted on a packing sleeve 9, and held against detachment therefrom by means of the annular collar 10, screwed onto the lower end of the sleeve. The lower end of the sleeve 9 is outwardly beveled as at 9', so that a bailer, used in bailing the well, will not engage against said lower end when the bailer is being elevated.

There is an expandible packing element 11 around the sleeve 9. This packing element is formed of any suitable packing material such, for example, as burlap or other fabric arranged in lengthwise overlapping strips on the sleeve 9. The lower end of the packing element surrounds the upper end of the dog 6, and is clamped thereto by means of the surrounding band 12, and the packing element is clamped to the sleeve 9 by means of surrounding bands as 13, arranged at intervals, the upper one 60 of which is at the upper end of said element. A section of the sleeve within the packing element 11 has the peripheral annular ratchet teeth 14, having a left hand pitch, and adapted to interlock with the teeth 8, of 65 the locking dog 6, when the packing is expanded or set to hold said packing in expanded position.

The setting tool embodies a comparatively small tubing 15, whose upper end is threaded into the bushing 16, which in turn is threaded into a collar 16', and this collar is threaded by means of left hand threads into the collar 17, carried by the sleeve 9. The upper end of this collar is outwardly flared, or beveled, as at 17', to prevent the bailer, when used, from hanging thereon. When assembled in position to be lowered into the well, an operating string of pipe 22 is connected to the collar 16'. The lower end of the tubing 15 has an annular sleeve like anchor 18 fastened thereto whose upper end has an annular depending rib 18'. There are radially operating supporting arms 19 notched to receive said rib 18' and the lower ends of these arms are normally held

- expanded by the coil springs 20, which are interposed between them and the anchor 18 said springs being of sufficient rigidity to hold the supporting arms in proper position.
- 5 When in assembled position these arms are located in the lower end of the nipple 3, with their lower ends resting against the inside annular shoulder 21, and the nipple 3, to hold the device rigid and prevent the packer from collapsing until it is ready to be set.

The entire device is let down into the well by means of the string of pipe 22, connected to the upper end of the collar 16', the parts being held against relative turning by the brass pin 25. When the lower end of the well screen attached to the liner 2 is seated on the bottom of the bore and it is desired to set the packer the string 22 is turned to the right to unscrew the collar 16' from the collar 17, and the string 22 is then elevated to carry the lower ends of the arms 19 above the upper end of the sleeve 9, and the springs 20 will expand said arms until their lower ends are in position to rest upon the upper end of said sleeve. The string is then lowered and the weight thereof will shear the pin 25, and gradually force the lower end of said sleeve down through the dog 6, and the nipple 3. The upper sections of the packer, between the bands 13 will move downwardly with the sleeve 9, but the lower section or end of said packing element will abut against the rib 5, and be expanded, and as the sleeve is further lowered the sections of the packer, between the surrounding bands will be expanded in succession from the bottom upwards. Consequently, there will be no appreciable friction of the packing element against the outer pipe as the packing element moves downwardly, but each section will move downwardly to position for setting, before it is expanded against the outer pipe, the lengthwise packing strips bulging out between the bands or wire wrappings 12 and 13.

When the packing is set, the sleeve 9 will have moved downwardly a sufficient distance to permit the ratchet teeth 8 and 14 to engage and the dog 6 will thus be held in position to lock and hold the packing element in expanded position.

The setting tool may then be withdrawn from the bore through the string 22.

55 Threaded into the lower end of the tubing 15 there is a reducer nipple 23 which is internally threaded to receive the upper end of the usual wash pipe 24, if it is desired to use the same.

60 In some cases it may be desired to release the packer. In such case a string of pipe is let down into the bore and connected in any approved manner to the collar 17, and then turned to the right to unscrew the packing sleeve 9 from the dog 6, so as to

disengage their teeth and an upward pull will then release, or collapse, the packing element 11 and permit its withdrawal.

What I claim is:—

1. A packing device including a tubular 70 nipple whose lower end is reduced forming an inside shoulder and adapted to be connected to a liner beneath, a collar connected to the upper end of the nipple, an annular dog connected to said collar whose lower 75 end is vertically slotted forming fingers whose inner faces have ratchet teeth, a packing sleeve on which said dog is slidably mounted, means holding the dog against detachment from said sleeve, an expandable 80 packing element around the sleeve, the lower end of which is attached to said dog, a section of the sleeve within the packing being provided with ratchet teeth adapted to engage with the teeth of said fingers, all in 85 combination with a setting tool capable of movement into upper or lower position relative to the packing device and embodying a tubing within said sleeve and whose upper end is connected to the sleeve and an annular sleeve like anchor fastened to the tubing, radially operating supporting arms whose upper ends are connected to said anchor, yieldable means holding the free ends of 90 said arms expanded into position to rest on the inside annular shoulder of said nipple when the setting tool is in its lower position, said yieldable means operating to carry the lower ends of said arms above the upper end of said sleeve when the setting tool is 95 in its upper position.

2. A packing device including a tubular nipple whose lower end is reduced forming an annular shoulder and adapted to be connected to a liner beneath, a collar connected to the upper end of the nipple, an annular dog connected to said collar whose lower end is vertically slotted forming fingers whose inner faces have ratchet teeth having a left hand pitch, a packing sleeve on 100 which said dog is slidably mounted, means holding the dog against detachment from said sleeve, an expandable packing element around the sleeve, the lower end of which is attached to said dog, a section of the sleeve within the packing being provided 105 with ratchet teeth having a left hand pitch 110 adapted to engage with the teeth of said fingers, all in combination with a setting tool capable of movement into upper or lower position relative to the packing device and embodying a tubing within said sleeve and whose upper end is connected to the sleeve and an annular sleeve-like anchor fastened to the tubing, radially operating 115 supporting arms whose upper ends are connected to said anchor, yieldable means normally holding the free ends of said arms expanded into position to rest on the inside annular shoulder of said nipple when the 120 125 130

setting tool is in its lower position, said yieldable means operating to carry the lower ends of said arms above the upper end of said sleeve when the setting tool is in its 5 upper position.

3. A packing device including a tubular nipple whose lower end is reduced forming an inside shoulder and adapted to be connected to a liner beneath, a collar connected 10 to the upper end of the nipple, an annular dog connected to said collar whose lower end is vertically slotted forming fingers whose inner faces have ratchet teeth, a packing sleeve on which said dog is slidably 15 mounted, means holding the dog against detachment from said sleeve, an expansible packing element around the sleeve, the lower end of which is attached to said dog, said packing element being formed of packing 20 material arranged in overlapping strips and bands spaced apart around said element, the upper band being at the upper end of said element, a section of the sleeve within the packing being provided with ratchet teeth 25 adapted to engage with the teeth of said fingers, all in combination with a setting tool capable of movement into upper and lower position relative to the packing device and embodying a tubing within said sleeve and 30 whose upper end is connected to the sleeve and an annular sleeve-like anchor fastened

to the tubing, radially operating supporting arms whose upper ends are connected to said anchor, yieldable means normally holding the free ends of said arms expanded into 35 position to rest on the inside annular shoulder of said nipple when the setting tool is in its lower position, said yieldable means operating to carry the lower ends of said arm above the upper end of said sleeve when 40 the setting tool is in its upper position.

4. A packer adapted to be connected to an operating string of pipe and including two telescoping members, one of said members being connected to said pipe by left 45 hand threads, an expansible packing element surrounding said last named member, an abutment carried by the other member against which the adjacent end of the packing element is adapted to abut, the lower 50 end of the last named member being reduced, a tube connected to said string of pipe, expansible arms pivotally connected at their upper ends to said tube and whose lower ends are adapted to rest against said 55 reduced end of said member and yieldable members normally tending to hold said arms in expanded position.

In testimony whereof I have signed my name to this specification.

HARRY THOMSON.
